Primary Examiner — Cynthia R Underwood(74) *Attorney, Agent, or Firm* — Stiennon & Stiennon(57) **CLAIM**

The ornamental design for a rope saddle and anchor for a rope caddy, as shown and described.

DESCRIPTION

FIG. 1 is top isometric view of the rope saddle and anchor for a rope caddy of the invention, the broken lines in the figures illustrate the portions that form no part of the claimed design;

FIG. 2 is a bottom isometric view thereof, with a rope carried thereon shown in broken lines as environmental matter;

FIG. 3 is a top plan thereof;

FIG. 4 is a front elevational view thereof, a portion of a rope is shown in broken lines as environmental matter;

FIG. 5 is right side elevational view, the side opposite being a mirror image thereof.

FIG. 6 is a rear elevational view thereof, with a rope carried theron shown in broken lines as environmental matter; and,

FIG. 7 is a bottom plan thereof.
